US00D681725S

(12) **United States Design Patent**
Kishimoto et al.

(10) **Patent No.:** **US D681,725 S**
(45) **Date of Patent:** **** May 7, 2013**

(54) **PRINTER**

(75) Inventors: **Ai Kishimoto**, Nagoya (JP); **Jiro Suzuki**, Nagoya (JP)

(73) Assignee: **Brother Industries, Ltd.**, Nagoya (JP)

(**) Term: **14 Years**

(21) Appl. No.: **29/412,400**

(22) Filed: **Feb. 2, 2012**

(30) **Foreign Application Priority Data**

Aug. 23, 2011 (JP) 2011-19009

(51) **LOC (9) Cl.** **14-02**

(52) **U.S. Cl.**

USPC **D18/55; D14/467**

(58) **Field of Classification Search** D18/19, D18/36-38, 50, 52, 54, 54.1, 55; D14/420-425, D14/462-470; 400/613, 613.1-613.4, 690.1-690.4, 400/691-694

See application file for complete search history.
